INVENTOR:
RICHARD KENNELL

By Harry A. Birne
ATTORNEY.

UNITED STATES PATENT OFFICE.

RICHARD KENNEDY, OF ST. LOUIS, MISSOURI, ASSIGNOR OF ONE-THIRD TO SETH RANDALL, OF ST. LOUIS, MISSOURI.

SHOE.

Application filed November 8, 1926. Serial No. 147,027.

My invention has relation to improvements in shoes and the method of making same, and consists in the novel features of construction more fully set forth in the specification and pointed out in the claims. The object of the invention is to produce a shoe of any style that possesses great flexibility, neatness and comfort, and this object is accomplished by constructing the shoe with but a single sole. I have completely dispensed with the customary inner sole, as in my improved shoe the single sole presents a smooth surface on both sides and renders an inner sole, as a separate part of the shoe, unnecessary. Another great advantage of my improved shoe is that a high quality product can be more cheaply manufactured than under the present methods of construction. Further and other advantages will be better apparent from a detailed description of the invention in connection with the accompanying drawings, in which—

Figure 1 is a perspective view of my improved shoe, having parts broken away; Figure 2 is a perspective view of the sole prepared for the process of manufacture according to my invention; Figure 3 is a face view of the steel shank; Figure 4 is a cross-section taken through the sole and upper in the process of construction on the last; Figure 5 is a cross-section through the counter, sole, and upper on the last; Figure 6 is a cross-section through the finished shoe taken on the line 6—6 of Figure 1.

Referring to the drawings, L represents the last on which the shoe is built and to which the sole 1 is tacked. The sole 1 entering into the construction of my improved shoe, is first properly prepared from the blank by being contoured as shown in Figure 2. Then a channel 2 is formed entirely around the margin of the sole from one side of the breast 3 to the other. The leaf 4 formed in the channeling operation is then turned or folded back to be out of the way for subsequent operations. The sole 1 is then split from the heel 5 to the break 6. The sole 1, thus prepared, is tacked onto the last and the upper 7, with the counter 8 in place, stretched thereover. The operator now draws the upper tightly over the last, bringing the margin of the upper under the

channeled part of the sole, and then stitches the upper to the sole through the channel 2. The upper is stitched (preferably on a Puritan machine) entirely around the channel, i. e. from one side of the breast 3 to the other (see Figure 4). The next operation is to last the heel seat 9 by tacking to the heel part 5 of the sole 1 (see Figure 5).

The operator now places a welt 10 around the margin of the upper and stitches (preferably on a Goodyear machine) through the welt, upper and sewing lip a of the sole 1 from one side of the breast of the sole to the other. The channel leaf is still turned up, as shown dotted in Figure 6, at this stage of the operation. The shank 11 is now inserted between the sole proper and the turned up flap 12, after which the flap is turned down and the channel leaf 4 brought down over the stitching and cemented firmly in place so that the stitches are neatly covered over and protected, and the bottom of the sole presents a perfectly smooth, clean appearance.

The heel 13 may now be nailed in place, and the edge of the shoe trimmed. Whatever finishing operations are necessary may now be performed to complete the job.

As above pointed out, a shoe made as above described, combines the advantages of simplicity, low cost, neatness, flexibility, and, of course, comfort for the wearer.

It is obvious that the invention is susceptible of certain modifications, and I do not herein restrict myself to either the precise features or operations in manufacturing above described.

Having described my invention, I claim:

1. A shoe embodying an upper and a single sole, said sole having its margin channeled from one side of the breast to the other to form a channel leaf and sewing lip, and split from the heel part to the break of the ball portion, a metallic shank cemented into the sole between the layers thereof formed by the split, the margin of the upper and a welt thereover stitched to the sewing lip of the sole, the said channel leaf being cemented over the stitches, and a heel secured to the heel seat.
2. A shoe embodying an upper and a single sole, said sole having its margin chan-

neled from one side of the breast to the other to form a channel leaf and sewing lip, and split from the heel part to the break of the ball portion, a metallic shank cemented into the sole between the layers thereof formed by the split, said upper having its margin stitched to the sewing lip, a welt disposed

over the margin of the upper and stitched to said lip, the aforesaid channel leaf being cemented over said stitches, and a heel secured to the heel seat of the sole. ¹⁰

In testimony whereof I hereunto affix my signature.

RICHARD KENNETT.
